US0D1011757S

(12) **United States Design Patent** (10) **Patent No.:** **US D1,011,757 S**
(45) **Date of Patent:** **** Jan. 23, 2024**

(54) **BODY OF ELECTRIC TOOTHBRUSH**

(71) Applicant: **GUANGZHOU MEIJIA INTELLIGENT TECHNOLOGY CO., LTD**, Guangzhou (CN)

(72) Inventors: **Jiaye Liao**, Guangzhou (CN); **Zhijian Yao**, Guangzhou (CN); **Siyuan Chen**, Guangzhou (CN); **Shuangshuang Li**, Guangzhou (CN); **Lixiang Huang**, Guangzhou (CN)

(73) Assignee: **GUANGZHOU MEIJIA INTELLIGENT TECHNOLOGY CO., LTD**, Guangzhou (CN)

(**) Term: **15 Years**

(21) Appl. No.: **29/796,618**

(22) Filed: **Jun. 25, 2021**

(51) LOC (14) Cl. **28-03**

(52) U.S. Cl.

(57) **CLAIM**

The ornamental design for a body of electric toothbrush, as shown and described.

DESCRIPTION

FIG. 1 is a front and right perspective view of a body of electric toothbrush showing our new design;

FIG. 2 is a rear and left perspective view of a body of electric toothbrush showing our new design;

FIG. 3 is a front elevation view of a body of electric toothbrush showing our new design;

FIG. 4 is a rear elevation view of a body of electric toothbrush showing our new design;

FIG. 5 is a left side elevation view of a body of electric toothbrush showing our new design;

FIG. 6 is a right side elevation view of a body of electric toothbrush showing our new design;

FIG. 7 is a top view of a body of electric toothbrush showing our new design; and,

FIG. 8 is a bottom view of a body of electric toothbrush showing our new design.

The broken lines showing various regions of the body of electric toothbrush represent unclaimed subject matter and form no part in the claimed design.

1 Claim, 8 Drawing Sheets
